DESIGN FOR A FONT OF TYPE

John A. Herbst, Oradell, N. J., assignor to Federal Telephone and Radio Corporation, Newark, N. J., a corporation of Delaware

Application August 20, 1943, Serial No. 110,964

Term of patent 3½ years

(Cl. D64—12)

To all whom it may concern:

Be it known that I, John A. Herbst, a citizen of the United States, residing at Oradell, in the county of Bergen and State of New Jersey, United States of America, have invented a new, original, and ornamental Design for a Font of Type, of which the following is a specification, reference being had to the accompanying drawing, forming part thereof.

The figure is a plan view of a font of type embodying my new design.

I claim:

The ornamental design for a font of type, as shown.

JOHN A. HERBST.
